DESIGN.

S. SMITH.

CARPET.

No. 13,129.

Patented Aug. 1, 1882.

Horace Druckbaum
Horace Druckbaum

Inventor
Stephen Smith

UNITED STATES PATENT OFFICE.

STEPHEN SMITH, OF PHILADELPHIA, PENNSYLVANIA, ASSIGNOR TO HORNER BROTHERS, OF SAME PLACE.

DESIGN FOR A CARPET.

SPECIFICATION forming part of Design No. 13,129, dated August 1, 1882.

Application filed June 21, 1882. Term of patent 3½ years.

To all whom it may concern:

Be it known that I, STEPHEN SMITH, of the city of Philadelphia, county of Philadelphia, and State of Pennsylvania, have invented and 5 produced a new and original Design for Carpets, of which the following is a specification.
The nature of my design is fully represented in the accompanying photographic illustration, to which reference is made.

I claim as my invention—

The design for a carpet, as shown.

Witnesses: STEPHEN SMITH.

GEO. B. KRICKBAUM,
HORACE KRICKBAUM.
